UNITED STATES PATENT OFFICE

109,414

DESIGN FOR A PEDESTAL DESK

William G. Meagher, Oakland, Calif., assignor to Standard Oil Company of California, San Francisco, Calif., a corporation of Delaware

Application February 25, 1938, Serial No. 75,401

Term of patent 14 years

To all whom it may concern:

Be it known that I, William G. Meagher, a citizen of the United States of America, residing in the city of Oakland and county of Alameda, State of California, have invented a new, original, and ornamental Design for a Pedestal Desk, of which the following is a specification, reference being had to the accompanying drawing, forming a part thereof.

In the drawing the figure is a perspective view of a pedestal desk showing my new design.

I claim:

The ornamental design for a pedestal desk, as shown.

WILLIAM G. MEAGHER.
